INDIRECTLY HEATED CATHODE

Max Knoll and Rudolf Rzehulka, Berlin, Germany, assignors to Telefunken Gesellschaft für Drahtlose Telegraphie m. b. H., Berlin, Germany, a corporation of Germany

Application July 10, 1934, Serial No. 734,464
In Germany May 4, 1933

4 Claims. (Cl. 250--27.5)

The present invention is concerned with an indirectly heated cathode for cathode ray or Braun tubes.

The technical problem involved in these tubes differs from that involved in an amplifier tube insofar as in the case of the Braun tube the chief consideration is not merely to insure as large an electron emission current as possible, as is true of the amplifier tube, but rather that the electrons given off from the cathode should pass through the anode (diaphragm) in the form of as slender or narrow a pencil as feasible and should thus enter into the space located posteriorly of the anode where the deflector plates and the like are mounted. In other words, such electrons as are given off by the cathode and which fail to flow through the anode diaphragm produce no other effect than that of raising the temperature of the anode; hence, this should be obviated as far as possible. In the case of Braun tubes which are to be used as receivers or transmitters for television work, arrangements moreover must be made so that the electron pencil emitted by the cathode must be capable of being acted upon by the so-called Wehnelt or focusing cylinder of a similar control means.

For these reasons, the form of indirectly heated cathode for Braun tubes heretofore generally employed and in which the cathode was built in such a way that it would give off electrons in all directions, but predominantly in a sense at right angles to the tube axis has been extremely unfavorable. For it will be understood that the electron emission current is in major part collected upon the anode, in other words, only a minor part of the electron pencil actually passes through the diaphragm or anode.

In order to obviate the drawbacks associated therewith, i. e., undesirable heating of the anode, in connection with an indirectly heated cathode, in other words, of a cathode in which the support with the electron-emitting substance has throughout the same potential, only a surface presenting a planar surface towards the anode, or a convex surface, should bear the electron emission substance, according to this invention.

In Braun tubes for television work, when using a form for the indirectly heated cathode according to this invention, there results still another advantage which consists in that the voltage (modulation voltage) applied to the Wehnelt or focusing cylinder or other control device serving to act upon the electron emission current, may be lower than under otherwise equal conditions.

5 A number of embodiments according to this in-

vention shall be described in what follows by reference to the accompanying drawing.

Referring to Fig. 1, 10 denotes the heater wire of the indirectly incandescent cathode, 11 is a sheet of metal positioned at right angles to the tube axis which is indicated by the line A, B. The said metal sheet supports upon its upper face turned towards the anode the electron emissive substance K. The sheet of metal 11 which is preferably of circular shape, may be secured upon 10 the filament 10 by hard-soldering (brazing) or may be welded together therewith at the point marked P, if desired, by the aid of a sheet-metal strip C.

Referring to Fig. 2, the reference symbols 10, 15 A, B, K, have the same denotations as in Fig. 1. The support 12 for the electron-emitting substance is also here positioned substantially at right angles to the tube axis A, B, and it supports the electron emissive substance K upon its face 20 turned towards the anode. The sheet 12 at the end opposite or turned away from the anode has an extension or projection 13 which is either welded together with the heater 10 or is merely secured thereon by clamping action.

According to another embodiment of this invention as illustrated in Fig. 3, the electron emissive substance K is supported upon the bottom surface turned towards the anode of a cylindrical hollow body 14 in which is accommodated 30 a preferably bifilar heating winding 16 separated therefrom by an insulation body 15. The bottom surface of the cylinder 14 turned towards the anode could also present a convex curvature in the direction of the anode.

In Figs. 4a-4c are shown embodiments of the invention in which the electron-emissive substance K is disposed upon the surface of an extension which is secured upon the bottom surface of a hollow cylinder according to Fig. 3, the 40 said bottom surface being either round or conical. The closing disk 20 in Fig. 4a consists also of insulating material.

The body being indirectly incandescent by the heater winding and denoted by 11, in Fig. 1, by 12 in Fig. 2, and 14 in Figs. 3 and 4, consists preferably of nickel or of a ferro-chromium alloy possessing and insuring a magnetic screening action in order that, if the heater wire is other than bifilar, the magnetic field set up by the 50 heater wire may be precluded, while when the heater wire is bifilar it may, as far as feasible, serve to keep the residual field of the heating current away from the discharge space between cathode and anode.

Having thus described the invention what we claim and desire to secure by Letters Patent is:

1. An unshielded point-source thermionic cathode comprising a hollow metallic cylinder closed at one end by a hollow solid of revolution having a projection of maturely reduced diameter at its apex, a non-conducting hollow cylinder planarly closed at one end disposed within the first of said cylinders with said planar surface adjacent to the closed end of the first of said cylinders, a filament winding disposed longitudinally within the second of said cylinders, and a thermionic emissive coating on the end portion of the exterior surface of the projection of the first of said cylinders.
- 15 2. An unshielded point-source thermionic cathode comprising a hollow metallic cylinder closed at one end by a hollow frustum of a cone, having a tip on its axis, a non-conducting hollow cylinder planarly closed at one end, disposed within the first of said cylinders with said planar surface adjacent to the closed end of the first of said cylinders, a filament winding disposed longitudinally within the second of said cylinders, and a thermionic emissive coating on the end portion of the exterior surface of the tip of the first of said cylinders.
- 20 25

3. An unshielded point-source thermionic cathode comprising a hollow ferro-magnetic cylinder closed at one end by a hollow frustum of a cone having a tip on its axis, a non-conducting hollow cylinder planarly closed at one end, disposed within the first of said cylinders with said planar surface adjacent to the closed end of the first of said cylinders, a filament winding disposed longitudinally within the second of said cylinders, and a thermionic emissive coating on the end portion of the exterior surface of the tip of the first of said cylinders.

4. An unshielded point-source thermionic cathode comprising a hollow ferro-magnetic cylinder closed at one end by a hollow solid of revolution having a projection of reduced cross sectional area at its apex, a non-conducting hollow cylinder planarly closed at one end, disposed within the first of said cylinders with said planar surface adjacent to the closed end of the first of said cylinders, a filament winding disposed longitudinally within the second of said cylinders, and a thermionic emissive coating on the end portion of the exterior surface of the projection of the first of said cylinders.
